TAIL FOR FISHING LURE

Walter W. Collins, 221 W. Knoxville,
Broken Arrow, Okla. 74012

Filed May 9, 1968, Ser. No. 11,863

Term of patent 14 years

U.S. Cl. D22—27
Int. Cl. D22—07FIG. 1

FIG. 2

FIG. 3

FIG. 4

FIG. 5

FIGURE 1 is a side elevational view of a tail for fishing lure, showing my new design.

FIGURE 2 is a top plan view thereof.

FIGURE 3 is an enlarged cross-sectional view taken on the line 3—3 in FIGURE 1.

FIGURE 4 is an enlarged cross-sectional view taken on the line 4—4 in FIGURE 1.

FIGURE 5 is an enlarged cross-sectional view taken on the line 5—5 in FIGURE 1.

I claim:

The ornamental design for a tail for fishing lure, substantially as shown and described.
